Term of patent 14 years

(Cl. D26—5)

To all whom it may concern:

Be it known that I, Clarence Karstadt, a citizen of the United States, residing at Glen Ellyn, in the county of Du Page and State of Illinois, have invented a new, original, an ornamental Design for an Electric Motor, of which the following is a specification, reference being had to the accompanying drawings, forming a part thereof, in which:

Fig. 1 is a side elevational view of an electric motor, showing my new design; Fig. 2 is an end elevation thereof looking from the right-hand side of Figs. 1 and 3; Fig. 3 is a plan view thereof; and Fig. 4 is an end elevational view of an electric motor looking from the left-hand side of Figs. 1 and 3.

This application is a continuation of my application, Serial No. D. 4,188, filed July 28, 1949, which in turn was a continuation of my application, Serial No. D. 146,493, filed May 20, 1948, both applications now being abandoned.

I claim:

The ornamental design for an electric motor,
as shown and described.

CLARENCE KARSTADT.
